UNITED STATES PATENT OFFICE.

GEORGE B. KEPLINGER, OF CHICAGO, ILLINOIS.

BROOM-HANGER.

1,362,996.

Specification of Letters Patent. Patented Dec. 21, 1920.

Application filed October 13, 1919. Serial No. 330,434.

To all whom it may concern:

Be it known that I, GEORGE B. KEPLINGER, citizen of the United States, residing at Chicago, in the county of Cook and State of Illinois, have invented certain new and useful 5 Improvements in Broom-Hangers; and I do hereby declare the following to be a full, clear, and exact description of the invention, such as will enable others skilled in the 10 art to which it appertains to make and use the same.

This invention relates to improvements in devices for hanging brooms and similar objects.

15 The particular object of the present invention is to provide a simple and efficient device of this character which is equipped with a broom handle supporting or engaging element adapted, when not in use, to be 20 swung against its supporting element on the wall so as to present no obstruction to passage and which is adapted to be turned into engaging relation with and to automatically engage and support the broom handle in- 25 serted therein so that the latter will, by its own weight, maintain it in such engagement against accidental removal.

The invention consists in the features of construction and combination of parts here- 30 after fully described and particularly claimed.

In the accompanying drawings illustrating a suitable embodiment of the invention,

35 Figure 1 is a view in front elevation of a broom hanger constructed in accordance with the invention, showing the same in its inoperative or idle position.

Fig. 2 is a side elevation of the same showing the broom handle engaging elements 40 thereof in engaging relation to a broom handle in dotted lines.

Fig. 3 is a top plan view of the device when in its operative position.

My said device comprises a suitable sheet 45 metal supporting plate 1, which is substantially rectangular in shape and is equipped with perforations 2 for the passage of suitable fastening devices for securing the same to a wall. At its lower end or along its lower 50 edge the said plate 1 is provided with a cylindrical sleeve formation 3 in which one of the horizontal arms of a U-shaped member 4 is pivotally engaged. The plate 1 is provided with a similar pivot sleeve formation 55 5 parallel with the sleeve 3 in which one of the horizontal arms of a U-shaped element 6

is engaged. Both said elements 4 and 6 are made of wire and the outer arm of the element 4 is provided with a projection 7 which, in the instance illustrated, consists of an extension of its outer arm folded upon its end and provided at its free end with a U-shaped formation 8 in which the middle portion of the member 6 is received and slidably engaged. The said middle portion of the members 4 and 6 are laterally offset from each other so that the middle portion of the member 6 intersects or contacts with the inner end portion of the outer arm of the member 4. The outer arm of the member 6 terminates preferably in a loop 9 for convenience in engaging the same and to prevent the presentation of a sharp edge.

The pivot sleeves 3 and 5 are preferably so formed or the nature of their engagement 75 with the arms of the members 4 and 6 engaged therein is such as to provide sufficient frictional resistance to the free pivotal movement of said members 4 and 6 as to prevent them from dropping by gravity 80 from their normal positions shown in Figs. 1 and 2.

The connection between the outer arm of the member 4 and the middle portion of the member 6 is such that both said members 85 4 and 6 will be caused to turn on their pivots in unison. As the latter are disposed at different elevations, the pivotal movement thereof downwardly from their normal positions shown in Figs. 1 and 2 will 90 cause the outer arms of said members 4 and 6 to approach each other and thus clamp an object disposed between the same firmly to support said object. The weight of said object tends to effect sufficient pressure upon 95 the members 4 and 6 to effect firm engagement and support of the object. To disengage the object it is only necessary to slightly lift the same and then move it out of the substantially U-shaped space formed between 100 the clamping arms and the middle portion of the member 6 as will be obvious. The user may then manually turn the members 4 and 6 back to the position shown in Figs. 1 and 2, thus maintaining them out of the 105 way of persons passing them.

The back or supporting plate 1 is long enough so that the ring 9 on the free end of the member 6 lies within the area of same when the two supporting elements are raised 110 against the plate. This extension of the plate 1 prevents the clamping elements mar-

ring the adjacent surface of the wall or woodwork and provides an area of appreciable extent upon which to display a suitable advertisement. As my device is extremely cheap to manufacture, I find its greatest market as an advertising device which can be made so cheaply that it can be given away free.

In order to reduce the cost of the manufacture I make the back plate 1 of extremely thin sheet-metal and I stiffen or strengthen the plate and prevent its being buckled or forced out of its true flat position, by means of a marginal rib 10 which is formed in the plate in the process of stamping same out. These ribs 10 are formed by pressing shallow grooves into the back of the plate and by this means I am enabled to greatly reduce the weight of the device and to increase its rigidity against being bent by the weight of a broom supported thereby. These ribs also serve to prevent the free removal of the arms of the two U-shaped clamping members which are mounted in the sleeves 3 and 5 as it is necessary to spring these members into the sleeves past the rib adjacent to the connected ends of the arms when mounting them in the sleeves.

I preferably form the free rearwardly extending ends 7 of the member 4 so that it will engage the middle portion of the member 6 with a frictional engagement which prevents the free falling of the two clamping elements when disengaged from a broom. This frictional engagement of the two elements can be produced without substantially any additional cost and is much more certain and positive in its action than the frictional engagement of the pivotally mounted arms in the sleeves 3 and 5.

While I have shown the preferred embodiment of the invention in the accompanying drawings, it will be obvious, of course, that such embodiment may be changed and varied in details of construction without departing from the invention as defined in the appended claims.

I claim as my invention:

1. A broom hanger comprising a supporting element adapted to be mounted on a wall, a U-shaped element having one of its arms pivotally engaged with said supporting element to swing on a horizontal axis, a companion similar element similarly pivotally engaged with said supporting element at a lower elevation than the first U-shaped element and having the free end of its other arm turned back upon itself to provide a sliding engagement with the middle portion of the first mentioned swinging element, whereby said U-shaped elements are caused to move pivotally in unison and their outer arms to move toward

and from each other during such pivotal movement.

2. A broom hanger comprising a supporting element and a pair of clamping elements pivotally engaged with said supporting element and having sliding engagement with each other for causing them to move pivotally in unison, and a projection on each of said clamping elements, the same being adapted to move toward and from each other to engage and disengage objects interposed between the same as said clamping elements are pivotally moved in one or other direction, said elements formed for mutual frictional engagement as and for the purpose specified.

3. A broom hanger comprising a supporting element and a pair of clamping elements pivotally engaged with said supporting element and having sliding engagement with each other for causing them to move pivotally in unison, the pivotal axes of said clamping members being horizontally disposed at respectively different elevations, and a projection on each of said clamping elements the same being adapted to move toward and from each other to engage objects interposed therebetween as the clamping elements are swung to cause their outermost ends to move downwardly, the engaged object adapted to be suspended from said clamping members and held engaged thereby by its own weight and a formed up rib on the supporting plate preventing the free removal of said clamping elements from their pivotal engagement with the plate.

4. In a device of the kind described, a supporting plate of quite thin sheet-metal provided with a marginal rib for stiffening the plate, two coöperating clamping members pivotally mounted on the plate adjacent to its lower end and at different heights whereby the clamping members tend to distort the plate when holding a broom, the clamping members being foldable up against the plate when not in use and the plate extending upwardly a sufficient distance to prevent the upper ends of the clamping members contacting with the wall above the plate.

5. In a device of the kind described, a supporting plate, two coöperating U-shaped members pivotally mounted on the plate at different heights, one of the members having its free end bent rearwardly and formed to clamp the middle portion of the other member with frictional pressure to prevent the free swinging of the two members.

6. In a device of the kind described, a wall plate made of thin sheet-metal provided with a marginal pressed in rib projecting from the face thereof, two hori-

- zontally extending sleeves on the face of the plate, two coöperating U-shaped clamping members each having an arm in one of the sleeves, the rib on the plate adjacent to the bodies of the clamping members preventing the free removal of the arms from said sleeve, the members having frictional engagement with each other to prevent the free swinging thereof.
- 5 7. In a device of the kind described, a wall plate, two coöperating U-shaped clamping members each mounted upon one
- arm upon the plate, the mountings being at different heights to cause their outer ends to approach each other as they are 15 swung on their mounted arms, the lower member being shorter than the upper member and its free arm bent back upon itself and formed to embrace the body of said longer member and bind it against the base 20 portion of said free arm to cause a frictional engagement of the two arms.

GEORGE B. KEPLINGER.
